UNITED STATES PATENT OFFICE.

SAMUEL C. MILLER, OF LOUISVILLE, KENTUCKY.

FILLING-TUBE FOR BOTTLE-FILLING MACHINES.

SPECIFICATION forming part of Letters Patent No. 738,622, dated September 8, 1903.

Application filed November 12, 1902. Serial No. 131,029. (No model.)

To all whom it may concern:

Be it known that I, SAMUEL C. MILLER, a citizen of the United States, and a resident of Louisville, in the county of Jefferson and State 5 of Kentucky, have invented a new and Improved Filling-Tube for Bottle-Filling Machines, of which the following is a full, clear, and exact description.

The invention relates to a class of bottle-filling machines embodying a vertically-adjustable tank from which liquid is conducted downward through self-closing tubes into a number of bottles supported below the tank to be filled therefrom. Improvements in this 15 class of bottle-filling apparatus are shown in my Patent No. 654,016 and dated July 17, 1900. The object of this invention is to provide improved filling-tubes for the bottle-filling machine specified that in suitable number 20 may be employed for the indicated purpose, whereby these similar members of the machine are greatly improved in operation.

The invention consists in the novel construction and combination of parts, as is hereinafter described, and defined in the appended claims.

Reference is to be had to the accompanying drawing, and characters of reference thereon, the single view shown representing a 30 transverse section of the liquid-holding tank and a vertical axial section of one of the improved filling-tubes.

The supply-tank 10 may be in the form of an oblong receptacle having parallel side 35 walls *a* and end walls *a'*, an essentially level bottom wall *b*, and a transversely-arched cover *c*, held secured upon the top of the tank-body by bolts *d*, that pass through flanges *e*, formed on the tank and cover.

40 In order to adapt the tank 10 for the vertical movement necessary for the proper operation of the machine, it is usual in this class of bottle-filling apparatus to mount it upon a suitable frame by a loose engagement of the ends of the tank with vertical guides and support it by springs or other means which will permit the tank to receive adjustment in a vertical plane when the operation of filling bottles is in progress. As the means for support and reciprocation of the tank 10 are not features of this invention, these details of a bottle-filling apparatus are not shown, it be-

ing understood that they may be constructed as may be preferred.

The bottle-filling tubes 11 of the improved 55 construction that constitute the present invention being alike in construction and arrangement, but one is shown in connection with the tank 10 and comprises the following details: The body of the tube 11 is of a suitable diameter to freely convey liquid from the tank 10 and is so proportioned in length that when placed in a vertical position in said tank a considerable portion of the filling-tube will extend below the tank, while the remaining portion projects upward through the lower wall *b* of the tank and also through a diaphragm-plate *g* into the cover *c*. In this construction the cylindrical body of the filling-tube 11 passes through a packing-box 12, that depends from 60 the bottom *b* and provides a liquid-tight joint, wherein the filling-tube is held to reciprocate. A suitable number of apertures *h* are formed in the wall of the filling-tube and are normally positioned in the body of the packing-box 12, the adjustment of the filling-tube to effect this disposal of the apertures *h* being effected by the coiled spring 13, that encircles 65 the filling-tube and presses at its upper end against the diaphragm-plate *g*, while the lower end of the spring is seated upon a collar 14, secured at a proper point on the filling-tube, and which defines the downward sliding movement of the filling-tube. A guide-block 15, 70 preferably shaped as shown, is secured by its lower end in an orifice in the diaphragm-plate *g*, and in said guide-block a vertical chamber *i* is formed, which receives the open upper end of the filling-tube 11. The shell or body of the filling-tube 11 is also open at 75 the lower end and receives the stem 16^a of the valve-head 16 therein. As shown, the valve-head is preferably conoidal, having an annular flat top surface that surrounds the lower end of the stem 16^a, forming a true seat 80 for the packing-ring *n*, that may engage the lower end of the filling-tube 11 and seal the joint between it and the valve-head. The valve-stem 16^a where it joins the valve-head 16 is diametrically enlarged, this enlargement 85 *n* tapering upward until it merges into the body of the valve-stem, this construction serving to center the valve 16 when the filling-tube is depressed to close the valve if the lat-

ter is opened, as will be hereinafter more fully described. The valve-stem 16^a extends upwardly through the filling-tube 11 and also through the chamber *i* in the guide-block 15, 5 having loose engagement within a perforation in the top wall of the guide-block, where by the valve-stem is held central in the chamber *i* and filling-tube 11. Upon the threaded upper end portion of the stem 16^a an adjustable nut *o* is screwed, which enables the seating of the valve-head 16 upon the lower end of the filling-tube 11.

Over the guide-block 15 for each filling-tube 11 an aperture *p* is formed, which is covered 15 by a cupped cap-piece *c'*, secured upon the cover *c*, as shown, this cap-piece being provided to permit the valve-stem 16^a to receive proper upward movement, as will be further explained.

20 An air-escape pipe 17 is placed in the filling-tube 11 at one side of the valve-stem 16^a and extends from the open upper end of said filling-tube down to a point near the lower end thereof, where a bend *s* is formed on the air- 25 escape pipe, directing its lower extremity toward the side wall of the filling-tube and through a perforation therein, said end *s'* of the pipe being secured air-tight in the wall of the tube 11. The upper end of the pipe 30 17 is open, so that air may pass freely through it, and thus conduct air into the chamber *i*, and to permit a free escape of air conducted upwardly by the pipe 17 a plurality of perforations *r* are formed in the side wall of the guide-block 15, which afford communication from the chamber *i* into the space inclosed between the dome-like cover *c* and the diaphragm-plate *g*.

Upon the filling-tube 11 below the tank 10 40 a sealing-head is adjustably mounted, consisting of a clamp 18, that may be held at a desired point on the tube 11 by a set-bolt *u*, a washer-plate 19, mounted upon the filling-tube below and in contact with the clamp 18, 45 and an elastic block 20 in washer form that is slid upon the tube 11 and by its contraction clasps said tube, so as to remain in place when adjusted to have contact with the washer-plate 19.

50 In service each one of a set of the improved filling-tubes is inserted within the neck of a supported bottle that is to be filled, the sealing-block 20 being properly positioned on the tube, so that lowering of the tank 10 and insertion of the filling-tube into the neck of a bottle will first effect a contact of the block 20 with the upper end of an engaged bottle, (not shown), and upon a further depression of the tank 10, which will slide the tube 11 55 upwardly, the lower end of the said tube will be elevated correspondingly, thus carrying the openings *h* into the tank 10 for the free transfer of liquid from the tank down the filling-tube. The compression of the spring 60 13, that is effected by the lowering of the tank 10, adapts said spring to depress the tube to normal height when the tank is raised.

The gravity of the valve-head 16 and valve-stem 16^a, together with that of the liquid passing downward from the tank 10, opens 70 the valve at the bottom of the filling-tube by dropping the valve-head until the nut *o* contacts with the guide-block 15, so that the liquid from the tank may freely enter the bottle-neck engaged by the filling-tube. While 75 filling the bottle air from the same escapes up the pipe 17 into the space in the tank-cover *c*, as before mentioned, and if air-pressure is formed in the receptacle it will be obvious that such pressure will be relieved by a downward flow of air when the tank is elevated and the filling-tube is removed from a filled bottle. In conducting the filling operation the liquid will rise in the neck of the bottle until it covers the lower open end of the air- 85 escape pipe 17, which will arrest the flow of liquid from the tank, and this will leave a small vacancy in the upper portion of the bottle-neck, the extent of which may be determined by an adjustment of the sealing-block 20, such a vacancy being necessary to permit the insertion of a cork into the bottle-neck.

Having thus described my invention, I claim as new and desire to secure by Letters 95 Patent—

1. The combination of a tank having a diaphragm dividing the same into an upper and a lower chamber, a hollow perforated guide-block in the upper chamber, a filling-tube 100 slideable in said guide-block, an air-tube extending through the filling-tube and discharging into the upper chamber through the apertures in the block, and a valve for the filling-tube adjustable from the guide-blocks, 105 substantially as set forth.

2. In a bottle-filling machine, a liquid-tank having an arched cover or lid, a horizontal diaphragm forming with said lid an independent chamber, said diaphragm having an 110 opening therein, a block fitting the sides of said opening and formed with an inner chamber, said latter chamber having openings in its walls forming communication between this chamber and the chamber first named, 115 a filling-tube open at its upper end and slideable within the said block, an air-tube passing within the filling-tube and having its upper end opening into the chamber in the said block, and a valve normally closing the lower 120 end of said filling-tube.

3. In a bottle-filling machine, a liquid-tank having an arched cover or lid, a horizontal diaphragm forming with said lid an independent chamber, said diaphragm having an 125 opening therein, a block fitting the sides of said opening and formed with an inner chamber, said latter chamber having openings in its walls forming communication between this chamber and the chamber first named, a filling tube open at its upper end and slideable within the said block, an air-tube passing within the filling-tube and having its upper end opening into the chamber in the said block, 130

and a valve normally closing the lower end of said filling-tube, said valve having a stem extending through the chamber in the block, and provided with adjusting devices therefor located beyond the upper end of the block.

4. The combination with a supply-tank, a diaphragm-plate, a dome-cover holding the diaphragm-plate clamped on said tank, and a centrally-chambered guide-block, having lateral openings therein for passage of air, said guide-block being mounted upon the diaphragm-plate, of an open-ended filling-tube slidable in the tank and guided at the upper end by engagement within the chamber of the guide-block, means pressing the filling-tube downwardly, a coniform valve flat on the upper end forming a seat thereon, a seal-

ing-joint between said valve and the lower end of the filling-tube, a valve-stem extending centrally from the top of the coniform valve up through the perforated top wall of the guide-block, an adjustable nut screwed upon the threaded upper end of the valve-stem, and an air-escape pipe held in the filling-tube at one side of the central valve-stem, and tapping the wall of said tube near the lower end thereof, substantially as set forth.

In testimony whereof I have signed my name to this specification in the presence of two subscribing witnesses.

SAMUEL C. MILLER.
